UNITED STATES PATENT OFFICE.

JAMES BUCHANAN LEPOO AND DAVID MARTIN LEPOO, OF MANSFIELD, OHIO, ASSIGNORS OF ONE-THIRD TO THOMAS HALL, OF MANSFIELD, OHIO.

CARBURETER FOR EXPLOSIVE-ENGINES.

SPECIFICATION forming part of Letters Patent No. 711,902, dated October 21, 1902.

Application filed August 13, 1901. Serial No. 71,915. (No model.)

To all whom it may concern:

Be it known that we, JAMES BUCHANAN LEPOO and DAVID MARTIN LEPOO, citizens of the United States, and residents of Mansfield, county of Richland, and State of Ohio, have invented new and useful Improvements in Carbureters for Explosive-Engines, of which the following is a specification.

Our invention relates to improvements in carbureters which are used in conjunction with vapor-engines, the carbureter shown in the drawings and described in the specification being especially constructed and adapted to be used in connection with a gasolene-engine of the portable type; and the objects of our improvements are, first, to afford facilities for mixing gasolene or other gaseous fluids with air in such proper and uniform proportions as will result in giving the engine its maximum efficiency under all conditions, such as the changing of temperature of the air, the vibration, changing and varying positions of the engine, carbureter, and running-gear caused by obstructions in and the irregular surfaces of the road; second, to construct a carbureter that will provide a means of bringing gasolene or other gaseous fluids and air to a common center in the mixing-chamber and dispersing them radially after being mixed in the form of gas through holes communicating with the engine supply-chamber; third, to provide a means of automatically supplying the carbureter, reservoir, and central feed or stand pipe with a uniform amount of gasolene (or other gaseous fluid) and maintaining a constant difference in level between the fluid in the stand-pipe and reservoir; fourth, to construct a carbureter that will maintain gasolene (or other gaseous fluid) in the stand-pipe at a constant height irrespective of the position of the carbureter; fifth, to provide a method of constructing a carbureter with a supply-chamber by means of which the vapor or gas will be drawn from the mixing-chambers into the engine supply-chambers and delivered to the cylinder of the engine, said gas retaining the same density; sixth, to provide a means whereby more or less gasolene (or other gaseous fluid) and air may be drawn into the mixing-chamber of the carbureter independent of each other;

seventh, to afford facilities for atomizing the gasolene (or other gaseous fluid) after it is forced into the mixing-chamber of the carbureter; eighth, to provide a means of varying the supply of air and gasolene simultaneously. We attain these objects by the mechanism illustrated in the accompanying drawings, in which—

Figure 1 is a vertical section of the entire carbureter. Fig. 2 is a bottom view of the circular float. Fig. 3 is a side view of the circular float. Fig. 4 is a horizontal sectional view through the carbureter, showing the location and construction of the coiled annular atomizers and the eccentric engine supply-chamber z' . Fig. 5 is a bottom view of the carbureter.

Similar letters refer to similar parts throughout the several views.

In the following description gasolene will be designated as the "fluid" used; but we do not limit ourselves to that fluid, as it is obvious that other gaseous fluids can be used without deviating from the principle of our invention.

A supply-tank (not shown in the drawings) is attached to the engine or running-gear at a higher plane than the carbureter and supplies it with gasolene (or other gaseous fluid) through suitable pipe connections by gravity.

The body or shell a of the carbureter has its lower portion b threaded interiorly to receive a vertical annular rib c , which is made integral with the bottom d . Said annular rib c is threaded exteriorly and is adapted to engage with the lower portion b of the carbureter, thereby forming a reservoir e for the reception of gasolene. The bottom d has a boss f , projecting downwardly, and is provided with an aperture f' , which is counter-bored, leaving the shoulder f^2 beveled to form a valve-seat. The gasolene flows through the aperture f' into the reservoir e , being forced by gravity through suitable pipe connections which are connected with the supply-tank. An annular float g , having an aperture g' in the center adapted to fit the projecting end h of the stand-pipe loosely, is inserted in the reservoir e . A yoke j is riveted or attached by any other suitable means to the bottom in the center of and immediately over the aper-

ture q' . Said yoke is provided with an aperture k , into which the threaded end of a valve-stem j' is inserted and retained in place by the nut j^2 . The opposite end of valve-stem j^3 is beveled to correspond and coincide with the valve-seat f^2 . The float is sustained by means of the gasoline, and its weight regulates the quantity of gasoline that flows into the reservoir e . A sufficient amount of gasoline is admitted into the reservoir to counteract the weight of the float and valve. The float is then forced upward in the reservoir, bringing the valve connected thereto in contact with the valve-seat, stopping the flow of gasoline until the quantity of gasoline in the reservoir is reduced to such an amount as will permit the float to move downward and open the valve. By this arrangement a constant level or quantity of gasoline can be maintained in the reservoir.

The stand-pipe m is made integral or may be fitted to the inside diameter of the shell and is supplied with gasoline through the aperture n . The stroke of the piston creates a vacuum in the stand-pipe, forcing the gasoline into the chamber o , filling it and supplying the mixing-chamber with the required amount of gasoline. The end h of the stand-pipe is counterbored, leaving the shoulder p beveled. The bore is threaded to receive a bushing p' , having its periphery threaded to engage with the threaded portion of the bore. A ball p^3 is inserted between the bushing and the bevel-shoulder and contacts with the beveled end of the bushing, acting as a check until the next vacuum-stroke of the piston, thereby keeping the stand-pipe full of gasoline. The top r of the stand-pipe and bottom r' of the cap s are formed conical in shape, the purpose of which is to force the air and gasoline to a common center or pivotal point, thereby providing a means to thoroughly mix the air and gasoline. The space t , outlined by the bottom of the cap and the top of the stand-pipe, forms a mixing-chamber. In the center of the cap and in alignment with the chamber o in the stand-pipe an aperture is provided, into which a dividing-point and sprayer s' , made integral, is inserted and is adjusted to and from the outlet in the chamber o by means of the nut s^2 . It is retained in place by the set-screw s^3 . The end of the dividing-point is tapered, and in connection with an annular downwardly-projecting rib u , made integral, performs the double function of admitting more or less gasoline into the mixing-chamber and dividing and spraying it. The amount of gasoline forced into the mixing-chamber is regulated by adjusting the dividing-point to and from the outlet in the chamber o , thereby increasing or decreasing the opening between the outlet and the tapered portion of the dividing-point. A ring v^2 , having an aperture in the center, with its top and bottom surfaces beveled to correspond with the bottom surface of the cap s and the top surface of the stand-pipe m , is

inserted in the mixing-chamber between the bottom of the cap s and the top of the stand-pipe and is retained in place by the frictional contact of its periphery with the inside surface of the mixing-chamber or by other suitable means. This combination and arrangement of the parts results in forcing the air and gasoline to a common center through the medium of annular V-shaped spaces y and also serves to retain the atomizers in place. The cap s has a downwardly-depending flange w , interiorly threaded, which is adapted to engage with the threaded exterior w' of the top portion of the carburetor. An annular groove w^3 is formed in part in the periphery of the carburetor and the cap and connects with the opening x . A series of apertures w^4 are provided in the circumference of the flange w and communicate with the groove w^3 . Air is drawn in the mixing-chamber through the apertures, groove, and opening. The supply of air or gasoline can be varied simultaneously by screwing the cap up or down, thereby increasing or decreasing the opening regulating the supply of air and the outlet in the chamber o which supplies gasoline to the mixing-chamber. The supply of gasoline or air can be regulated independent of each other by adjusting the cap or dividing-point separately. The lever h^2 is provided to screw the cap up or down and may be attached to the governor or any convenient hand device. A series of annular spiral atomizers x' of varying diameters are placed on the top of beveled surface of the stand-pipe and thoroughly atomizes the mixture. The spiral of each individual atomizer is turned right and left and are placed in the mixing-chamber with the spiral running in opposite directions alternately. We do not confine ourselves to the form of atomizers described, as modifications can be made without deviating from the principle involved in our invention. A series of apertures z are provided (the size and number can be varied) in the circumference of the carburetor and correspond with the surface of the stand-pipe. Said apertures communicate with the engine supply-chamber z' . This supply-chamber is of eccentric shape, the larger or wider portion of which chamber is connected to the engine by means of the outlet pipe or port z^3 . The radiating-apertures z connect the atomizing-chamber with the supply-chamber z' . Now it will be observed that when a vacuum is created in the outlet-pipe z^3 , owing to the backward stroke of the engine-piston, (not shown,) the air in the eccentric supply-chamber z' will rush into pipe z^3 . Since the pipe z^3 is connected to the larger or wider portion of the supply-pipe, the air only in the wider portion will be drawn into the pipe z^3 first, and air from the narrower portion thereof will rush to the front, drawing after it the vaporized and intermingled hydrocarbon and air from the radiating-ports z' of the atomizing-chamber, and as the vacuum is re-

duced an equal amount of vaporized com-
mingled air and hydrocarbon will be drawn
from each radiating-aperture z' into the out-
let-pipe z^3 until the suction caused by the
vacuum is entirely overcome. A vent-pipe
5 z^4 is provided to connect chamber e with the
atmospheric pressure and provides an over-
flow-pipe to prevent the flooding of the en-
gine in case of an obstruction causing the
leakage of the valve j^3 .

It will be noted that by means of the car-
bureter constructed as described, having its
stand-pipe and reservoir centrally located, a
defect common to carbureters is obviated—
15 that is, the plane of the level of the gasolene
passes through a fixed point in the center of
the stand-pipe regardless of the position of
the carbureter, and a uniform amount of gaso-
lene is delivered to the mixing-chamber at all
20 times.

The operation of our carbureter is as fol-
lows: Gasolene (or other gaseous fluid) is sup-
plied to a reservoir from a supply-tank by
gravity in uniform quantities and maintained
25 at a constant level by means of an automatic
valve. It is then forced into a central stand-
pipe by creating a vacuum therein by the
stroke of the piston of the engine which re-
moves the atmospheric pressure. The amount
30 of gasolene supplied to the mixing-chamber
is regulated by a dividing-point and sprayer.
The gasolene is retained in the stand-pipe
until the next vacuum-stroke of the engine
by means of a ball-check. The air and gaso-
35 lene are admitted into the mixing-chamber
through the annular groove and communi-
cating apertures described and stand-pipe
and carried over bevel-surfaces to a common
center, atomized and supplied to the engine
40 through an eccentric chamber or a chamber
so formed and adapted as to create an equal
vacuum.

Having fully described our invention and
its mode of operation, what we claim, and de-
45 sire to secure by Letters Patent, is—

1. A carbureter comprising a casing having
a reservoir, a central stand-pipe extending
into the reservoir, the upper surface of the
stand-pipe being inclined, a cap on the cas-
50 ing, the cap having its inner surface inclined
oppositely to the upper surface of the stand-
pipe, a ring having its upper and lower sur-
faces inclined toward the center, the cap and
upper surface of the central pipe together with
55 the ring forming a mixing-chamber, substan-
tially as described.

2. A carbureter comprising a casing, a res-
ervoir located in the bottom of the casing, a
stand-pipe, the lower end of which extends
60 into the reservoir, the upper end of the stand-
pipe of conical formation, the conical surface
leading to the outlet-port, a cap adjustably
secured on the casing, the cap being of in-
verted conical shape, and provided with a se-
65 ries of openings therein, the cap also provided
with an annular groove whereby to connect

the openings with one another and with the
interior of the casing.

3. A carbureter comprising a casing having
a reservoir located in the bottom thereof, a 70
stand-pipe, the projecting end of which de-
pends into the reservoir, the reservoir pro-
vided with an inlet-opening, means surround-
ing the stand-pipe and connected to the valve
whereby to control the opening, an inverted 75
conical cap located above the stand-pipe, a
dividing-point and sprayer secured in the cap
and projecting downwardly into the opening
in the stand-pipe, the cap provided with open-
ings leading to the atmosphere, and an an- 80
nular groove connecting the openings with
the interior of the casing, the cap provided
with adjustable means whereby the admis-
sion to the mixing-chamber of air and hydro-
carbon is simultaneously effected. 85

4. A carbureter comprising a casing pro-
vided with a reservoir, a stand-pipe depend-
ing into the reservoir, a ball-check located in
the stand-pipe, a mixing-chamber located at
the opposite end of the stand-pipe, means for 90
supplying air to the mixing-chamber, a ring
provided with beveled surfaces inclining to-
ward the mixing-chamber, the mixing-cham-
ber provided with outlet-passages, and spiral
atomizers located in the outlet-passages, the 95
atomizers retained in position by means of
the ring.

5. A carbureter comprising a shell, a cap
located thereon and having a screw-threaded
portion engaging an interiorly-threaded por- 100
tion of the shell, a stand-pipe, a beveled ring
located above the stand-pipe, a mixing-cham-
ber, a reservoir surrounding the depending
end of the stand-pipe, and a single means for
adjusting the cap whereby to regulate the ad- 105
mission of gasolene and air into the mixing-
chamber.

6. A carbureter comprising a shell provided
with a reservoir therein, a stand-pipe depend-
ing into the reservoir, positive means in the 110
stand-pipe for admitting and retaining an
amount of hydrocarbon therein from the
reservoir, a mixing-chamber at the opposite
end of the stand-pipe, a cap adjustably se-
cured on the upper portion of the shell, the 115
cap provided with an annular groove connect-
ing a series of openings with the interior of
the shell, a dividing-point and sprayer ad-
justably secured in and carried by the cap,
the depending end of the sprayer extending 120
into the upper open end of the stand-pipe,
the amount of air and hydrocarbon entering
the mixing-chamber being controlled by the
cap and sprayer, the cap being adjustable
whereby to regulate the entrance of both air 125
and hydrocarbon simultaneously and the
sprayer being adjustable whereby the sup-
ply of hydrocarbon may be regulated inde-
pendently of the air-supply or vice versa.

7. A carbureter provided with a shell hav-
ing a reservoir therein, a stand-pipe depend-
ing into the reservoir, the upper end of the

stand-pipe of conical shape, a cap of inverted conical shape adjustably secured in the shell opposing the conically-formed upper end of the stand-pipe, the cap controlling the air-
5 supply, a sprayer adjustably secured in and carried by the cap, the depending end of the sprayer projecting into the upper open end of the stand-pipe, a ring located in the shell between the cap and stand-pipe, the ring pro-
10 vided with surfaces inclining toward one another, and a plurality of atomizers placed one above the other and located in the space between the upper end of the stand-pipe and the lower face of the ring.

15 8. A carbureter comprising a shell having a reservoir therein, a stand-pipe depending into the reservoir, the upper end of the stand-pipe provided with a conical flange, an inverted-cone-shaped cap adjustably secured
20 in the shell, the cap controlling the air-inlet, a ring located between the stand-pipe and the cap, the ring provided with faces inclining toward the center of the shell, the inner circumference of the ring together with the
25 upper end of the stand-pipe and the cap forming a mixing-chamber with conical passages leading from the air-inlets, and to the discharge-orifices, means carried by the cap for regulating the discharge of hydrocarbon from
30 the stand-pipe, and a supply-chamber surrounding the shell and communicating with the mixing-chamber through the discharge-orifices, the supply-chamber of eccentric form, whereby the suction of the piston will
35 operate to draw an equal amount of mixed air and hydrocarbon from each discharge-orifice.

9. A carbureter comprising a shell, a mixing-chamber formed therein, a stand-pipe
40 opening into the mixing-chamber, a cap adjustably secured to the shell, the cap provided with apertures leading to the outer air, and an annular groove in the cap connecting the air-apertures with the air-passage leading
45 to the mixing-chamber, a sprayer and dividing-point adjustably secured in the cap, the lower end of the sprayer extending into the hydrocarbon stand-pipe and means on the cap whereby to simultaneously regulate the
50 amount of air and hydrocarbon supplied to the mixing-chamber, the sprayer also capable of independent adjustment with reference to the cap and stand-pipe.

10. A carbureter comprising a shell, a res-
55 ervoir removably secured therein and provided with an inlet-opening, a valve located in the opening, a stand-pipe depending into the reservoir, a float surrounding the stand-pipe, the valve connected thereto whereby

60 the inlet-opening is controlled, a ball-check located in the stand-pipe whereby to prevent hydrocarbon once admitted from returning to the reservoir, the upper end of the stand-pipe provided with a conical flange leading
65 to the discharge-ports, an inverted-cone-shaped cap adjustably secured to the shell, the cap controlling the admission of air there- |

to, a dividing-point and sprayer adjustably secured in the cap, the depending end of the sprayer adapted to enter the upper open end 70 of the stand-pipe, means for simultaneously or independently regulating the amount of air and hydrocarbon admitted to the mixing-chamber, a ring provided with upper and lower faces inclining toward the center, the 75 ring forming conically-shaped passages from the air-inlets to the mixing-chamber, and from the mixing-chamber to the discharge-outlets, and an eccentrically-formed supply-chamber surrounding the shell and communicating with the discharge-ports whereby the suction exerted by the piston will operate to draw an equal amount of mixed air and hydrocarbon from the mixing-chamber into the explosive-chamber. 80

11. A carbureter comprising a shell, a reservoir having an annular shoulder thereon, the reservoir removably secured to the shell and provided with an inlet-opening, a valve located in the opening, a stand-pipe depend- 90 ing into the reservoir, a float surrounding the stand-pipe, the shoulder limiting the downward movement of the float, the valve connected thereto whereby the inlet-opening is controlled, a ball-check located in the stand- 95 pipe whereby to prevent hydrocarbon once admitted from returning to the reservoir, the upper end of the stand-pipe provided with a conical flange leading to the discharge-ports, an inverted-cone-shaped cap adjustably se- 100 cured to the shell, the cap controlling the admission of air thereto, a dividing-point and sprayer adjustably secured in the cap, the depending end of the sprayer adapted to enter the upper open end of the stand-pipe, a 105 mixing-chamber, a removable lever connecting with the cap for simultaneously or independently regulating the amount of air and hydrocarbon admitted to the mixing-chamber, a ring provided with upper and lower 110 faces inclining toward the center, the ring forming conically-shaped passages from the air-inlet to the mixing-chamber and from the chamber to the discharge-outlets, and an ec- 115 centrically-formed supply-chamber surround- 120 ing the shell and communicating with the discharge-ports whereby the suction exerted by the piston will operate to draw an equal amount of mixed air and hydrocarbon from the mixing-chamber into the explosive-chamber, the shell beneath the flange on the stand- 125 pipe provided with a port leading to the atmosphere whereby to relieve any vacuum created therein and to disclose any irregularity in the operation of the hydrocarbon-inlet 130 valve.

12. A carbureter comprising a shell, a mix- 130 ing-chamber formed therein, air and hydro- carbon inlet ducts leading to the mixing- chamber, discharge-passages leading from the mixing-chamber, an eccentrically-formed supply-chamber connected to the engine at one point, the eccentrically-formed supply- chamber surrounding the shell and commu- 135

nicipating with the discharge-passage leading from the mixing-chamber by means of discharge-apertures, the eccentric supply-chamber being narrowest at the point farthest 5 from its connection with the engine whereby the suction caused by the instroke of the piston will operate to draw an equal amount of mixed air and hydrocarbon from each discharge-opening.

10 13. A carbureter provided with a reservoir, a stand-pipe means for supplying the stand-pipe with a uniform amount of gasolene, a ball-check located in and adapted to retain the gasolene in the stand-pipe, a mixing-

15 chamber, a series of spiral atomizers placed upon the upper portion of the stand-pipe one above the other, a ring having its upper and lower surfaces beveled and adapted to retain the atomizers in place, and means for sup-

20 plying air to the mixing-chamber.

14. A carbureter comprising a reservoir, a hollow stand-pipe depending thereinto, a mixing-chamber into which the upper end of the

stand-pipe discharges, means for admitting air to the mixing-chamber, means for regulating the amount of air and hydrocarbon to be admitted to the mixing-chamber, a ring located above the stand-pipe, a series of coiled annular atomizers located between the ring and the upper end of the stand-pipe, and an 25 eccentric supply-chamber encircling the mixing-chamber, the mixing-chamber provided with discharge-orifices opening into the supply-chamber, the supply-chamber connected to the engine, the width of the supply-chamber being narrower at the point farthest from its connection with the engine.

Signed by us at Mansfield, in the county of Richland and State of Ohio, this 1st day of August, 1901.
